UNITED STATES PATENT OFFICE.

CALVIN H. EDINGER, OF FAIRVIEW, WEST VIRGINIA.

VESSEL-PROPELLED DEVICE.

1,229,729.

Specification of Letters Patent. Patented June 12, 1917.

Application filed July 6, 1916. Serial No. 107,851.

To all whom it may concern:

Be it known that I, CALVIN H. EDINGER, a citizen of the United States, residing at Fairview, in the county of Marion, State of West Virginia, have invented a new and useful Vessel-Propelling Device; and I do hereby declare the following to be a full, clear, and exact description of the invention, such as will enable others skilled in the art to 10 which it appertains to make and use the same.

This invention relates to the art of vessel propelling apparatus, and particularly to the kind employing a jet of steam, air or other fluid forced under pressure through or escaping from a port in the stern or the bow of the vessel, the stern and the stem or the bow being so shaped that the volume of propelling fluid or jet of steam is more or less 20 confined, whereby its force may be utilized to the best advantage in the propulsion of the vessel.

A further object of the invention is to provide means consisting of a valve or rotating member for directing the jet of steam or air or stream of fluid, either toward the forward or the stern end of the vessel.

A further object of the invention is to provide a gate valve at the forward or rear end 30 of a conduit, for cutting off the water from entering the conduit, when the jet of steam or other fluid is cut off.

In practical fields, the details of construction may necessitate alterations falling within 35 the scope of what is claimed.

The invention comprises further features and combinations of parts, as hereinafter set forth, shown in the drawings and claimed.

In the drawings:—

40 Figure 1 is a view in side elevation of a vessel, showing the same equipped with the improved means for propelling the same.

Fig. 2 is a view partly in elevation and partly in section longitudinally of the vessel 45 and its propelling means.

Fig. 3 is an enlarged detail sectional view for controlling the jet of steam or other fluid.

Fig. 4 is a sectional view on line 4—4 of 50 Fig. 3.

Fig. 5 is a sectional view on line 5—5 of Fig. 4.

Referring more especially to the drawings, 1 designates the hull of a vessel, and 2 a conventional form of marine boiler having 55 a steam dome 3, into which the steam from

the boiler collects, and which dome is provided with a pipe 4 leading therefrom. Arranged adjacent the bottom of the hull is a conduit 5, which consists of the sections 6, 60 7 and 8, which are joined together, as shown at 9. The sections 8 are provided with the usual or conventional construction of gate valve casements 10 having gate valves 11. The ends of the conduit are provided with meshwork bulbs 12, which are spherical or rounded, so as to deflect drift articles, and which bulbs are constructed of heavy metallic rod fabric or meshwork, so that a jet of steam or air or other fluid may 65 escape therethrough. The central section 6 of the conduit has an annular boss 13 rising upwardly therefrom, there being a cap ring plate 14 annular in cross section secured upon the boss by means of the 70 threaded rods 15 and jam nuts 16. Extending through the opening 17 of the boss is a nozzle 18 provided with a right angle extending portion 19 at its lower end, which portion is provided with an outlet jet opening 20. The boss 13 is provided with annular channel or groove 21 to receive packing 22. A sleeve 23 fits telescopically upon the nozzle, and partly through the cap ring plate 14, and is designed to engage and hold 75 the packing 22 securely in the channel 21. The sleeve 23 has an annular flange 24, through which said threaded rods 15 extend, so that by means of the nuts 25, the lower end of the sleeve 23 will jam down upon the 80 packing. A collar 26 having a handle 27 is secured upon the pipe valve by the set bolt 28, whereby the nozzle may be rotated, so that the right angle extending portion 19 with its jet opening may be turned toward 85 the stem or the stern of the vessel, whereby a jet of steam or other fluid may be shot through the conduit in either direction, which jet of steam or other fluid passes out through the bulb members 12 to impact 90 the water, the expansive force of the fluid being utilized after the impact, to propel the vessel forwardly. Telescoping the upper end of the nozzle is a sleeve 29 having an annular flange 30, in which the 95 screws 31 are threaded. Arranged adjacent the upper end of the sleeve 29 is a suitable packing 32, and telescopically fitting the upper end of the sleeve 29 is a coupling sleeve 33, into which the steam pipe 4 is 100 threaded, as shown clearly in Figs. 1, 2 and 4. The interior cylindrical surface of the

sleeve coupling has an annular rib 34, which bears down upon the packing 32. The screws 31 are threaded into the annular flange 35 of the sleeve coupling, and by 5 means of the nuts 36 the packing 32 is held secure. The upper end of the nozzle has an annular flange 37 which engages with the annular rib 34. Referring more especially to Fig. 4, it is to be observed that the 10 sleeve coupling and the cap ring plate 14 are connected by means of an integral bar 38, and since the screws 15 are threaded into the boss 13, and the collar 26 is interposed between the two sleeves 23 and 29, vertical 15 movement of the nozzle and the other parts of the structure are prevented, and by means of the screws 15 and 31, the sleeves may be moved axially from each other. The pipe 4 is provided with the usual form of valve 20 39, whereby the steam through the pipe 4 may be cut off and prevented from passing through the nozzle. The adjacent ends of the sleeves 23 and 29 form abutments 40 for the collar 26, and since the collar 26 is 25 secured by a set bolt 28 to the valve, said pipe valve is prevented from vertical movement. It will be seen that by moving the handle 27 the pipe valve may be rocked or rotated partially, so that the right angle extending portion may be directed toward the 30 stem or the stern of the vessel, for propelling the same forwardly or rearwardly.

The invention having been set forth, what is claimed as new and useful is:—

In a vessel propelling apparatus, the combination of a conduit arranged adjacent the bottom of the vessel from the stem to the stern and a steam supply pipe, of a coupling connection between the steam supply pipe and the conduit, a nozzle mounted in 35 said coupling connection and provided at its lower end with a right angle extending portion having a jet opening, means for partially rocking said nozzle to turn the jet opening toward the stem or the stern of the 40 vessel, said coupling connection comprising a cap plate secured to the conduit, a sleeve surrounding the lower portion of the nozzle and connected to the cap plate, a second sleeve surrounding the nozzle at its upper 45 end portion, and between which second sleeve and the first sleeve said rocking means is interposed, a coupling sleeve connected to the second sleeve and in turn connected to the steam pipe, and means connecting the 50 coupling sleeve and the cap plate.

In testimony whereof I have signed my name to this specification in the presence of two subscribing witnesses.

CALVIN H. EDINGER.
